BOAT

Ernest D. Cacciocarne, 17246 Simonds St.,
Granda Hills, Calif. 91344

Continuation-in-part of abandoned design application
Ser. No. 243,538, Apr. 12, 1972. This application Oct.
18, 1972, Ser. No. 298,459

Term of patent 14 years

Int. Cl. D12—06

U.S. Cl. D12—62

FIG. 1.

FIG. 2.

FIG. 4.

FIG. 3.

FIG. 6.

FIG. 5.

FIG. 7.**FIG. 9.****FIG. 8.****FIG. 11.****FIG. 12.**

FIG. 1 is a top plan view of a first embodiment of a boat showing the ornamental design of my present invention;

FIG. 2 is a front elevational view thereof;

FIG. 3 is a side elevational view thereof;

FIG. 4 is a back elevational view thereof;

FIG. 5 is a frontal perspective view thereof;

FIG. 6 is a rear perspective view of said first embodiment of my design;

FIG. 7 is a top plan view of a second embodiment of my ornamental design for a boat;

FIG. 8 is a side elevational view thereof;

FIG. 9 is a front elevational view thereof;

FIG. 10 is a rear elevational view thereof;

FIG. 11 is a rear perspective view thereof; and

FIG. 12 is a frontal perspective view of said second embodiment of my ornamental design for a boat.

This is a continuation-in-part of design application Ser. No. 243,538, filed Apr. 12, 1972, and now abandoned. I claim:

The ornamental design for a boat, as shown and described.
